TILTING APPARATUS

Kurt Schlesinger, Berlin, Germany

Application July 27, 1933, Serial No. 682,473
In Germany July 30, 1932

7 Claims. (Cl. 250—36)

For the production of recording screens with the assistance of tilting apparatus a connection system is required, which enables:

(1) The image frequency and the line frequency to be varied continuously and at will independently of each other for the purpose of producing synchronism with the transmitter;

(2) Adjustment of the size of image without variation of the once adjusted frequencies and 10 without distortion of the tilting potential curves, as desired, and

(3) (For example by the variation of corresponding biases) displacement of the position of the centre point of the image, i. e., of the entire image, in both co-ordinates on the screen of the receiver, for example the Braun tube, without in this connection affecting any of the previously adjusted parameters.

If the apparatus is linked up with the house 20 circuit, it is necessary to accomplish that synchronism is not disturbed even in the case of the greatest fluctuations ($\pm 20\%$) which may occur in the house-circuit potential.

The subject matter of the invention is a tilting 25 connection which fulfils in proper fashion all of the requirements referred to. A further particular advantage of the connection system according to the invention resides in the fact that the same enables both the line as well as 30 the image-change tilting device to be fed by one and the same rectifier.

The tilting device according to the invention is illustrated by way of example in the drawings. In this connection Figs. 1-4 show details 35 of the arrangement, whilst in Figs. 5 and 6 there is illustrated the total arrangement.

Fig. 1 shows the part of the arrangement serving 40 for regulation of the size and for adjustment of the middle point of the image component.

It is known that the time-linear tilting curve (saw-tooth curve) employed practically throughout at the present time for television purposes is composed harmonically of a large number of 45 overtones. It has been found that the potential distribution of the curve thus produced must include all of these harmonics in equal fashion, i. e., the same must operate independently of frequency up to at least the tenth overtone. The 50 problem is of particular importance, as the amplitude of the potentials delivered by the tilting generator is pre-determined by the operation thereof—for example, in the case of the glow lamp connection, the connection system with 55 grid glow lamps with and without hot cathode, and connections with electronic tubes, etc.,—and a direct variation of this amplitude at the generator is from a practical standpoint only capable of being performed with great difficulty without simultaneous variation of the frequency.

According to the invention the regulation of the amplitude takes place with the assistance of a frequency-independent distribution of the potential, with the use of ohmic resistances.

The tilting condenser 1 in the manner known per se is connected in parallel with a glow lamp 2 or another discharge element responding to amplitude surge values. The charging takes place through the medium of a charging tube 3 with a potential-independent charging current as constant as possible. According now to the 10 invention, provision is made for the connection together of two potentiometers 4 and 5, of which 15 4 serves for variation of the form and 5 for variation of the position. The value of 4 should be selected in such fashion that the current traversing 4 is always smaller than approximately 1% of the charging current, so that the form 20 of the tilting curve is not varied. An upper limit for the resistance value of 4 is given by the condition that the same must remain without 25 angle up to the stated high harmonics of the number of image changes. This condition is simple to comply with, exactly in connection with the image change with resistances of the order of 10^5 ohms. The potentiometer 5 serves simultaneously for earthing purposes and for adjustment of the shifting potential.

As set forth more particularly at a later point, it is preferable to earth this resistance at a fixed 30 point and to select the same with an ohmic value as low as possible, for example in such fashion that the same takes over a current of the order of the charging current.

The connection system according to Fig. 1—if 35 necessary with corresponding variation of the resistance values—may naturally also be employed for the line device (the fundamental oscillation of which is approximately of the order of 2,500 periods). It is however, particularly 40 convenient, as set forth in Fig. 2, to provide a suppression condenser 6 in front of the size-adjustment potentiometer 4.

The condenser has fundamentally the object of withholding the plate current passing out of the 45 Braun tube from the charging circuit 3, 1. In this manner synchronization troubles, which are frequently caused by the connected Braun tube, particularly when the latter operates with strong currents, are precluded. Naturally these charging 50 troubles, in accordance with the invention, may also be overcome in other fashion, for example by the use of a filter chain, which does not allow passage of the light-control high frequency, and direct current, in the connecting 55 line 7 leading to the Braun tube.

Since in the arrangement according to Figs. 1 and 2 it is fundamentally compulsory to earth a certain middle pole of the operating batteries determined by the centre point of oscillation of 60

the tilting device, it is impossible to earth one of the two feed bar 20 or 21 of the battery 22 (Fig. 3). If, therefore, requirement exists for adjustment of two different earth points in the two components 23 and 24 for the two axes, it is necessary to operate with two different potential sources for the image and line components, as otherwise the potentials of the two lead lines would not agree in relation to earth, and a part 10 of the battery would be short-circuited. According to the invention, the earth point 25 of the image changing device and the earth point 26 of the line changing device—without consideration to the particular centre point of oscillation existing with regard to the two components 23 and 24—are so adjusted that no further compensating current traverses the connecting line 25, 26. Displacement of the position of the centre point of oscillation on the image screen may then be compensated by means of the potentiometers 5 and 10. It is desirable to employ tilting relays 2 and 11 with as far as possible the same electrical data. According to the invention, this is possible in particularly ready fashion if in 20 place of cold glow lamps there are employed tilting glow lamps with hot cathodes.

The connection system according to the invention enables the two tilting devices to be fed quite readily from the same current source (for example, from the same rectifier).

Since under certain circumstances a mutual effect may be exerted by the line tilting potential and the image tilting potential, tuning-out elements are provided in accordance with the invention, for example in the form of the resistances 12, 13 and the condensers 14, 15. Naturally in place of this simple condenser-resistance chain there may be employed any other filter chain which is incapable of being passed by the line frequency and its harmonics, for example a low-pass filter. At the same time the feed of the image-change portion of the system may take place through the medium of filter elements 16, 17, which prevent the passage of all oscillations 40 which are higher, for example, than the image-change frequency itself.

If necessary, there must also be provided in the common earth line filters, which allow the passage merely of the frequencies of the particular generator connected at the time, and block 50 those to the side thereof.

It has been found that when employing, for example, good controllable grid glow tubes with hot cathodes, and more particularly when making use of charging through the medium of tubes having a small reciprocal of the amplification factor, fluctuations in the house-circuit potential produce strong effects of flow. Synchronism is destroyed entirely with a fluctuation in potential 55 amounting to $\pm 3\%$. The disturbance is explained according to extent and direction by increase of the charging current of the charging tube 3 in Fig. 4, which arises from the fact that the grid or grids of this three-electrode or four-electrode tube becomes more positive as compared with the hot cathode upon an increase in the potential of the network anode 27. Early ignition then takes place at the glow device 2.

This disturbance may be overcome in accordance with the invention by the use of a glow gap divider of the kind known per se in place of the ohmic potential divider 5 otherwise employed.

An additional connection system for eliminating the stated error, in which solely ohmic resistances are employed, is illustrated in Fig. 4.

According to the invention, a resistance 30 is connected in the cathode line.

This resistance imparts to the cathode 28 of the charging tube an additional negative bias as compared with its grid, which is compensated by displacement of the grid-connection point 29 at the potentiometer 5. The resistance 30, with suitable size, exerts a considerable stabilizing effect, cause the drop in potential at the same produces a variation of the effective grid bias in the charging tube, which acts exactly in opposition to the detrimental influence of the fluctuation in the network. It is possible, for example, with a resistance of 10,000 ohms and a charging current amounting on an average to 5 milliamperes to 15 raise the detrimental limit in respect of the fluctuation in the network potential from $\pm 3\%$ to $\pm 15\%$. The resistance 30 is preferably not bridged for the tilting frequency produced. The same then causes dynamically an improvement 20 in all errors in form otherwise produced by relaxation of the current of the charging tube.

In Fig. 5 there is shown by way of example the complete arrangement, according to the invention, of a network tilting apparatus operated with 25 central source of current. 1 and 2 are the two network-heated screening grid charging tubes, 3 and 4 the charging condensers, and 5 and 6 grid glow tubes with hot cathode and filling of gas. To overcome spark disturbance there are employed filter chain 7, 8 or 9, 10 and also the screening hoods 11 and 12. The stabilizing and curve-improving resistances are designated 13 and 14. The image-tilting device, which is arranged in the screen box 11, operates with a purely galvanic distribution of the potential over the potentiometer 15, the size-adjusting potentiometer, and the potentiometer 16, the position-adjusting potentiometer. In the line component the corresponding potentiometers are designated 17 and 18. In addition to these there is the blocking device 19, which has been described with regard to its effect, and which overcomes the disturbing influence of the connected tube. The single-battery operation is rendered possible by 45 correctly bridge-balanced earthing points 20 or 21 of the potentiometers 16 and 18. Filter chains 22, 23, 24 ensure that the two oscillation components are not superposed. The condenser 25 serves to remove the line curvature. The filter chain member 26 causes analysis of the line or image-changing tone transmitted by the sending station into its two components. The pick-up takes place at the terminals 27 for the vertical co-ordinate and 28 for the horizontal co-ordinate. 55 The synchronizing impulses arrive at the terminal 29. Central earthing for the entire system is situated at 30. The network anode itself is steadied as well as possible by a large block 31.

According to the invention, a simplification 60 may be obtained at this point by the use of glow lamp stabilizers.

In Fig. 6 there is illustrated by way of example a form of embodiment of the arrangement according to the invention employing glow gap dividers. In this figure 31 and 32 are two series-connected glow-gap dividers, which if necessary may be replaced by one single suitably dimensioned potential divider, and 34 and 35 iron wire hydrogen resistances, which are provided in the heating line of the feed tubes. As shown by the drawings, the use of a single-way rectifier 33 is quite readily possible in the case of this connection system. The steadyng means may be considerably simplified.

The following values may for instance suitably be employed for the arrangement illustrated in Fig. 6.

34=1.0 amp. 4-12 volts
 35=1.0 amp. 4-12 volts
 36=6000 ohms (wire-resistance)
 37=0.3 $\cdot$ 10⁶ ohms
 38=3000 ohms
 39=10,000 ohms
 40=0.3 $\cdot$ 10⁶ ohms
 41=0.3 $\cdot$ 10⁶ ohms
 42=5 $\cdot$ 10⁶ ohms
 43=100,000 ohms
 44=25,000 ohms
 45=2000 ohms
 46=3 $\cdot$ 10⁶ ohms
 47=2 $\cdot$ 10⁶ ohms
 48=100,000 ohms
 49=10,000 ohms
 50=5 $\cdot$ 10⁶ ohms
 51=5,000 ohms
 52=2 $\cdot$ 10⁶ ohms
 53=3 $\cdot$ 10⁶ ohms
 54=100,000 ohms
 55=25,000 ohms
 56=1,000 ohms
 57=1 $\cdot$ 10⁶ ohms
 58=4 mf.
 59=2 mf.
 60=2
 61=0.0001
 62=1
 63=0.0003
 64=4
 65=0.0001
 66=0.01
 67=0.01
 68=2
 69=0.008
 70=0.005
 71=0.02
 72=2
 73=0.01
 74=2 $\times$ 300 volts
 75=4 volts

76 are the connections for the vertical deflecting plates,

78 are the connections for the horizontal deflecting plates,

77 are the connections for the synchronizing voltage.

The arrangement as shown otherwise agrees in substance with the arrangement according to Fig. 5. The single elements may be selected in the manner shown in the drawings; naturally, however, it is also possible to modify the values of any of these. As shown by the drawings, the rating of the two tilting tubes should not take place from the same source, as in this case disturbing couplings would take place.

The arrangement according to the invention makes it possible for the first time to vary the frequency, the form and the position of the image as desired completely independently of each other. For feeding the two tilting devices merely a single current source is required. The influence of the network potentials is reduced to a minimum.

It is possible with the arrangement according to the invention to vary both the width as well as the height of the image as desired. It is preferable, however, to maintain the form of image, the ratio between width and height, constant, example equal to the form of the transmitted image. According, therefore, to the invention,

the operating buttons of the two potentiometers determining height and width of the image may be coupled together mechanically in such fashion that the ratio between height and width remains constant in connection with each size of image. Naturally the coupling may be made variable, so that it is possible to adjust any desired form. (By the term "form" as here employed there is understood the shape and not the dimensional size of the image.)

I claim:

1. Means for producing tilting oscillations having a direct and a variable current component comprising a unidirectional source of potential, a condenser, means for charging said condenser from said source, said condenser and said charging means being connected across said source, means for discharging said condenser, independent means for adjusting said direct and said variable current component, said means for adjusting said direct current component comprising a potentiometer resistance connected across said source, said means for adjusting said variable current component comprising a second potentiometer resistance, the one end of said second potentiometer resistance being connected to a tapping point of said first potentiometer resistance and the other end between said condenser and said charging means, and output connections, one being connected to a second tapping point of said first potentiometer resistance, said second tapping point being connected to an earthed point and the other output connection being connected to a point on said second potentiometer resistance.

35

2. Means for producing tilting oscillations having a direct and a variable current component comprising a unidirectional source of potential, a condenser, means for charging said condenser from said source, said condenser and said charging means being connected across said source, means for discharging said condenser, independent means for adjusting said direct and said variable current component, said means for adjusting said direct current component comprising a potentiometer resistance connected across said source, said means for adjusting said variable current component comprising a second potentiometer resistance and a second condenser in series, the free end of said second potentiometer resistance being connected to a tapping point of said first potentiometer resistance and the free end of said second condenser between said condenser and said charging means, and output connections, one being connected to a second tapping point of said first potentiometer resistance, said second tapping point being connected to an earthed point and the other output connection being connected to a point on said second potentiometer resistance.

60

3. Means for producing tilting oscillations having a direct and a variable current component comprising a unidirectional source of potential, a condenser, means for charging said condenser from said source, said condenser and said charging means being connected across said source, means for discharging said condenser, independent means for adjusting said direct and said variable current component, said means for adjusting said direct current component comprising a potentiometer resistance connected across said source, said means for adjusting said variable current component comprising a second potentiometer resistance of 10⁶ ohms, the impedance of the charging circuit and of the first potentiometer

65

70

75

- resistance being proportioned to the resistance of the second potentiometer resistance so that the charging current and the current through the first potentiometer resistance are of the same order of magnitude and the current through the second potentiometer resistance is less than 1% of the charging current, the one end of said second potentiometer resistance being connected to a tapping point of said first potentiometer resistance and the other end between said condenser and said charging means, and output connections, one being connected to a second tapping point of said first potentiometer resistance, said second tapping point being connected to an earthed point and the other output connection being connected to a point on said second potentiometer resistance.
4. In combination two devices for producing tilting oscillations each having a direct and a variable current component, said devices being connected to one unidirectional source of potential, each device comprising a condenser means for charging said condenser from said source, said condenser and said charging means being connected across said source, means for discharging said condenser, independent means for adjusting said direct and said variable current component, said means for adjusting said direct component comprising a potentiometer resistance connected across said source, said means for adjusting said variable current component comprising a second potentiometer resistance, the one end of said second potentiometer resistance being connected to a tapping point of said first potentiometer resistance and the other end between said condenser and said charging means, and output connections, one being connected to a second tapping point of said first potentiometer resistance, said second tapping point being connected to an earthed point and the other output connection being connected to a point on said second potentiometer resistance.
5. In combination two devices for producing tilting oscillations, the one device producing an oscillation of low frequency for image deflection and the second device producing an oscillation of higher frequency for line deflection, each oscillation having a direct and a variable current component, said devices being connected to one unidirectional source of potential, said device for producing low frequency comprising a condenser and means for charging said condenser and filter elements having a high impedance to said higher frequency connected in series across said source, said device for producing higher frequencies comprising a condenser and means for charging said condenser connected in series across said source and high pass filter means having a cutoff at said low frequency connected between said source and said series combination of condenser and charging means, separate means for discharging each condenser, independent means for adjusting said direct and said variable current component of each oscillation wave, said means for adjusting said direct current component comprising a potentiometer resistance across the series combination of the condenser and charging means, said means for adjusting said variable current component comprising a second potentiometer resistance, one end of said second potentiometer resistance being connected to a tapping point on said first potentiometer resistance and the other end between said condenser and said charging means, and output connections,

one being connected to a second tapping point of said first potentiometer resistance, said second tapping point being earthed and the other output connection being connected to a point on said second potentiometer resistance.

6. In combination two devices for producing tilting oscillations each having a direct and a variable current component, said device being connected to one unidirectional source of potential, each device comprising a condenser, means for charging said condenser from said source, said condenser and said charging means being connected across said source, means for discharging said condenser, independent means for adjusting said direct and said variable current component, said means for adjusting said direct current component comprising a potentiometer resistance connected across said series combination of condenser and charging means, said means for adjusting said variable current component comprising a second potentiometer resistance, the one end of said second potentiometer resistance being connected to a tapping point of said first potentiometer resistance and the other end between said condenser and said charging means, and output connections, one being connected to a second tapping point of said first potentiometer resistance, said second tapping point being connected to an earthed point and the other output connection being connected to a point on said second potentiometer resistance, filter means comprising resistances between said source and one series combination of condenser and charging means and condensers between the terminals of said source and said ground.

7. In combination two devices for producing tilting oscillations, the one device producing an oscillation of low frequency for image deflector and the second device producing an oscillation of high frequency for line deflection, each oscillation having a direct and a variable current component, said devices being connected to one unidirectional source of potential, said source comprising a glow gap divider connected across a common supply network, each device comprising a condenser, a screening grid tube for charging said condenser from said source, a grid controlled gas filled hot cathode discharge tube for discharging said condenser, the grid of said discharge tube being connected to a synchronizing impulse line, independent means for adjusting said direct and said variable current component, said means for adjusting said direct current component comprising a potentiometer resistance connected across said source, a connection between the control grid of said charging tube and a point on said potentiometer, the screen grid of said charging tube being connected each to tapping points of said potentiometer resistance, said means for adjusting said variable current component comprising a second potentiometer resistance, the one end of said second potentiometer resistance being connected to a further tapping point of said first potentiometer resistance and the other end between said condenser and the anode of said screen grid tube, and output connections, one being connected to a second tapping point of said first potentiometer resistance, said second tapping point being earthed and the other output connection being connected to a point on said second potentiometer resistance.

KURT SCHLESINGER.
